CHARLES HARDY, OF NEW YORK, N. Y., ASSIGNOR TO AMSCO PRODUCTS INC., OF NEW YORK, N. Y., A CORPORATION OF NEW YORK.

VARIABLE RESISTOR.

Application filed December 23, 1924. Serial No. 757,874.

This invention relates to electrical resistance units, and has special reference to the provision of variable resistors or resistance devices.

5 A prime desideratum of my present invention relates to the production of variable resistors or resistance devices especially designed for use in controlling electron discharge tube and other circuits in radio receiving sets. As is well known, one of the methods of controlling the volume, tone and other operating characteristics of a radio receiving set is by regulating the filament current to control the electron emission of 10 the electron discharge tubes, this being accomplished by the adjustment of a variable resistor placed in the filament or tube circuit.

The type of variable resistor commonly 20 employed for this use comprises a stator which includes a resistance element such as a wire wound unit and a pair of connectors or binding posts, one of which is electrically connected to the resistance element, and a 25 rotor which includes an operating shaft and a contact blade fixed thereto, which contact blade is movable over the resistance element. In this type of construction, two regions must be relied upon for establishing electrical 30 connection between the rotor and stator parts, one being the point of engagement between the movable blade and the resistance element, and the other being the point of connection between the operating shaft and 35 the second binding post; and for the efficient operation of the tube circuit and the radio receiving set, it is necessary to establish or make efficient and continuous electrical connections at both regions. In prior constructions 40 of these variable resistors, the contact blade, which is made of a resilient material, is usually relied upon to bring the stator and rotor parts at both regions into the desired electrical engagement. It is found, 45 however, that the contact blade can not be made strong enough to effectively perform its intended functions and that the connection between the shaft and second binding post is interfered with by dust or other foreign matter settling between the parts, and as a consequence, such electrical engagement as is obtained in these resistors is insufficient to avoid microphonic noises in the telephones 50 due to the presence of microphonic contacts between the stator and rotor parts during

adjustment. A principal object of the present invention resides in the provision of an improved variable resistor in which electrical contact between the rotor and stator parts at all points or regions thereof is effectively 60 established, with the construction such that all microphonic noises in the receiver are eliminated during adjustment control of the filament circuit, such adjustment being obtainable smoothly and with a high degree 65 of precision.

Other and further prime objects of the invention include the provision of a variable resistor in which the electrical engagement between the stator and rotor parts at the 70 different regions thereof is obtained by resilient elements acting in opposition, each assisting the other in producing the desired electrical contact between adjacent stator and rotor parts; the further provision of a 75 variable resistor of the nature referred to in which the parts which are depended upon for producing the electrical engagement are, wherever feasible, effectively housed or sealed against the entry of foreign matter 80 so that the same are always maintained in clean condition and good operating service; and the still further provision of a variable resistor in which the parts are relatively coordinated to permit not only the rapid 85 assembly of the parts into a salable unit, but quick and efficient assembly of the parts of the resistor properly coordinated on a panel or like support.

To the accomplishment of the foregoing 90 and such other objects as will hereinafter appear, my invention consists in the elements and their relation one to the other, as hereinafter particularly described and sought to be defined in the claims; reference being 95 had to the accompanying drawings, which show the preferred embodiment of my invention, and in which:

Fig. 1 is a cross-sectional view of the variable resistor of my invention showing the 100 same mounted on a panel or like support.

Fig. 2 is a view taken in cross-section in the plane of line 2-2, Fig. 1, and

Fig. 3 is a perspective view of the parts 105 of the resistor in detached formation.

Referring now more in detail to the drawings, the improved resistor of my invention comprises a stator unit *s* constructed for attachment to a panel or like support, and a rotor *r* rotatably mounted in the stator. 110

The stator *s* is preferably of the wire wound type, comprising an arcuate-shaped resistance element or unit 10 formed, as is well known to those skilled in the art, by coiling a wire 10^a of suitable resistance about a flexible insulating core 10^b, the said resistance unit being bent into curved or arcuate form and clamped by a flexible clamping element 11 in an arcuate-shaped channel 12 provided in a supporting base 13, which supporting base is preferably made of an insulating material such as a molded phenol condensation product. The stator further includes the usual pair of binding posts 14 and 15 serving as connectors for the circuit conductors, the binding post 15 being connected to one terminal or lead of the resistance coil 10^a, and the binding post 14 being connected in a manner to be described presently to other parts of the stator unit.

As heretofore stated, a principal object of the present invention centers about the provision of a variable resistor in which electrical contact between the rotor and stator parts at relatively movable points or regions thereof is effectively established, with the construction such that all microphonic noises in the radio receiving system of which the resistor forms a part are effectively eliminated during adjustment control of the filament circuit. To contribute towards this desired end, the stator of my invention comprises an element which may be described as a connector element, the same functioning as a connecting means between a rotor part and the binding post 14. This connector comprises in the preferred construction a tubular shaped element 16 fixedly attached to the insulating base 13, the said connector element having an irregular, such as a square or hexagonal-shaped head 16^a seated in a correspondingly shaped central depression in the insulating base 13, the said connector element being externally threaded as at 16^b for receiving a clamping nut 17 and a panel mounting nut 18.

The connector element 16 is electrically connected to the binding post 14 by means of the metallic strip 19, one end of which is joined to the binding post 14, and the other end of which is clamped between the clamping nut 17 and a central boss portion 13^a of the insulating base. These parts of the stator define or comprise a unit which is mountable on a support such as a panel *p* by means of the panel mounting nut 18, which as shown in Fig. 1 of the drawings, is threadedly received by the outer end of the connector element 16. Preferably, as shown in the drawings, the face of the clamping nut 17 adjacent to the panel mounting nut 18 is made flush with the rim 13^b of the insulating base, so that the parts may be securely fastened to the panel by screwing the panel mounting nut 18 on the

threaded end of the connector without straining the insulating base. If desired, the insulating base may also be provided with a bore 20 for receiving additional means for securing the stator to the panel. 70

The rotor *r* of my invention comprises an operating shaft 21 mounted for rotation in the connector element 16, and a resilient contact blade 22 which is fixed to said shaft in a manner to be described presently, and which is arranged to be movable in engagement with a wall of the resistance element 10, as clearly shown in the drawings. In the preferred construction as exemplified in the drawings, the operating shaft 21 is threaded at one end, as at 21^a; and the movable contact blade 22 is fixed to a threaded nut 23 which is received by the threaded end 21^a of the operating shaft and is locked thereto by means of a lock nut 24, suitable washers 25 and 26 being interposed between the lock nut 24 and an annular lip 23^a which is integral with the nut 23 and which clamps the blade 22 in fixed position on the nut. 80

By means of this construction, the contact blade 22 is securely connected both mechanically and electrically to the operating shaft 21, and this construction, as will be shown presently, assists in permitting the obtaining of the desired operation of the rotor and the electrical connection between the same and the connector 16. 90

For producing the desired electrical contact or connection between the connector 16 and the binding post operating shaft 21, I provide a spring 27 arranged to effect electrical connection between the shaft and the connector element, the said spring being correlated or associated with the resistor parts so as to act in opposition to the resilient contact blade 22, the contact blade and spring functioning each to assist the other in producing the desired electrical engagement between contiguous rotor and stator parts. 100

The spring 27 to this end preferably comprises a compression spring, the said spring being arranged in the tubular-shaped connector 16 and encircling the shank of the operating shaft 21, the ends of the spring bearing axially in opposite directions on shouldered portions of the operating shaft and connector element respectively, as clearly shown in Fig. 1 of the drawings. As will be apparent, this spring is active on the shaft 21 in a direction which is transmitted to the resilient contact blade 22 to assist in making good electrical contact between the same and the resistance element 10, and conversely, the contact blade 22 is re-active on the shaft 21 in a direction to move the shaft against the spring 27 so as to secure good electrical engagement between both ends of the spring 27 with the shaft 21 and connector 16. Thus at both regions of con- 110

nection between the rotor and the stator, effective electrical contact is established. It will also be noted that the tubular connector element 16 is constructed to serve as a bushing or bearing of substantial length for the operating shaft, and that the said connector desirably serves as a protective housing and complete enclosure for the spring 27 so that the same may be sealed against the entry of foreign matter and the spring maintained in clean condition and in good operating service.

The manner of making and assembling the improved resistor of my invention and the many advantages thereof will be fully apparent from the above detailed description thereof. It will be apparent that the parts of the resistor unit may be readily assembled for purposes of separate sale; and when it is desired to attach the resistor to a panel, the same may be rapidly disassembled and connected to the panel by the purchaser or user without altering the predetermined cooperation between the parts. Thus the stator unit *s* will first be attached to the panel *p* by screwing the panel mounting nut 18 onto the threaded end of the connector element 16, which end is inserted through a bore provided in the panel. After thus securing or clamping the stator units rigidly in position on the panel, the operating shaft 21, after receiving the spring 27, is inserted through the connector element 16, the end of the shaft 21 being thereafter threaded into the nut 23 of the contact blade 22, the limit of this threading action being determined by a shoulder portion 21^b provided in the shaft 21, which shoulder portion abuts the outer face of the panel mounting nut 18. In threading the shaft 21 onto the nut 23, however, a slight amount of axial play is provided for so as to minimize any binding action between the parts and so as to permit the spring and contact blade to act in opposition to each other. The nut 23 is then securely locked in position on the operating shaft by means of the lock nut 24. The operating shaft 21 is provided with a finger grip or control handle 28 which is secured thereto by means of the screw 29. The parts may thus be assembled in a facile manner on the panel, with the predetermined arrangement of the stator and rotor parts properly coordinated.

While I have shown and described my invention in the preferred form, it will be apparent that many modifications and changes may be made in the structure disclosed without departing from the spirit of the invention, defined in the following claims.

I claim:

1. A variable resistor comprising a stator member including a supporting base, a resistance element mounted thereon and a connector element fixed thereto, a rotor member including an operating shaft rotatable but held against axial movement in said base and a movable resilient contact blade fixed to said shaft and movable over said resistance element, and a spring located between and arranged to bear axially in opposite directions on said shaft and said connector element, the resilient contact blade and the spring being correlated to act in opposition, each functioning to assist the other in producing efficient electrical engagement between a rotor part and a stator part.

2. A variable resistor comprising a stator member including a supporting base, a resistance element mounted thereon and a tubular shaped connector element fixed thereto, a rotor member including an operating shaft rotatable in said connector element and a movable contact blade fixed to said shaft and movable over said resistance element, and a spring located between and arranged to bear axially in opposite directions on said shaft and said connector element, the said tubular connector element forming a bushing for the shaft and a housing for the spring.

3. A variable resistor comprising a stator member including a supporting base, a resistance element mounted thereon, a connector element fixed thereto and a pair of binding posts connected respectively to the connector and resistance elements, a rotor member including an operating shaft rotatable but held against axial movement in said base and a movable resilient contact blade fixed to said shaft and movable over said resistance element, and a spring located between and arranged to bear axially in opposite directions on said shaft and said connector element, the resilient contact blade and the spring being correlated to act in opposition, each functioning to assist the other in producing efficient electrical engagement between a rotor part and a stator part.

4. A variable resistor comprising a stator member including a supporting base, a resistance element mounted thereon, a tubular shaped connector element fixed thereto, and a pair of binding posts connected respectively to the connector and resistance elements, a rotor member including an operating shaft rotatable in said connector element and a movable resilient contact blade fixed to said shaft and movable over said resistance element, and a spring located between and arranged to bear axially in opposite directions on said shaft and said connector element, the resilient contact blade and the spring being correlated to act in opposition, each functioning to assist the other in producing efficient electrical engagement between adjacent rotor and stator parts, the said tubular connector element forming a

bushing for the shaft and a housing for the said spring.

5. A variable resistor comprising a stator member including a supporting base, a resistance element mounted thereon and a connector element fixed thereto, a rotor member including an operating shaft threaded at one end rotatable in said base and a resilient contact blade having a threaded nut received by and locked to said shaft, said blade being movable over said resistance element, and a spring arranged between said shaft and said connector element and active axially on said shaft, the contact blade and the spring being correlated to act in opposition.

6. A variable resistor comprising a stator member including a supporting base, a resistance element mounted thereon, a threaded connector element fixed thereto, and a panel mounting lock nut threadedly receivable by said connector element, a rotor member including an operating shaft rotatable in said base and a movable contact blade fixed to said shaft and movable over said resistance element, and a spring arranged between said shaft and said connector element and active axially on said shaft.

7. A variable resistor comprising a stator member including a supporting base, a resistance element mounted thereon, and a tubular-shaped connector element fixed thereto, a rotor member including an operating shaft, threaded at one end, rotatable in said connector element and a movable contact blade having a threaded nut received by and locked to said shaft, said blade being movable over said resistance element, and a spring electrically connecting said shaft and said connector element, the contact blade and the spring being correlated to act in opposition, each functioning to assist the other in producing efficient electrical engagement between adjacent rotor and stator parts.

8. A variable resistor comprising a stator member including a supporting base, a resistance element mounted thereon, a threaded tubular-shaped connector element fixed thereto, and a panel mounting nut threadedly attached to said connector element, a rotor member including an operating shaft threaded at one end, rotatable in said connector element and a resilient movable contact blade having a threaded nut received by and locked to said shaft, said blade being movable over said resistance element, and a spring electrically connecting said shaft and

said connector element, the contact blade and the spring being correlated to act in opposition each functioning to assist the other in producing efficient electrical engagement between adjacent rotor and stator parts.

9. A variable resistor comprising a stator member including a supporting base, a resistance element mounted thereon, a threaded tubular-shaped connector fixed thereto and a panel mounting nut threadedly attached to said connector element, a rotor member including an operating shaft, threaded at one end, rotatable in said connector element and a resilient contact blade having a threaded nut received by and locked to said shaft, said blade being movable over said resistance element, and a compression spring located between and arranged to bear axially in opposite directions on said shaft and said connector element, the said tubular connector element forming a bushing for the shaft and a housing for the spring, the resilient contact blade and the spring being correlated to act in opposition, each functioning to assist the other in producing efficient electrical engagement between adjacent rotor and stator parts.

10. A variable resistor comprising a stator member including an insulating supporting base, a wire wound arcuate-shaped resistance element mounted thereon, a threaded tubular-shaped connector fixed thereto, binding posts connected respectively to said resistance and connector elements, and a panel mounting nut threadedly attached to said connector element, a rotor member including an operating shaft, threaded at one end, rotatable in said connector element and a resilient contact blade having a threaded nut received by and locked to said shaft, said blade being movable over said resistance element, and a compression spring located between and arranged to bear axially in opposite directions on said shaft and said connector element, the said tubular connector element forming a bushing for the shaft and a housing for the spring, the resilient contact blade and the spring being correlated to act in opposition, each functioning to assist the other in producing efficient electrical engagement between adjacent rotor and stator parts.

Signed at New York city, in the county of New York and State of New York, this 15th day of December, A. D. 1924.

CHARLES HARDY.
